UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,396**, dated September 9, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

A zigzag-shaped figure, A, traverses the carpet and appears to divide the same into an upper portion, B, and a lower portion, C.

The figure A contains a series of fern-leaves and some flowers, partly on and over a geometrical groundwork, a. The upper field, B, contains a fanciful rectangular figure, b, which somewhat resembles the letter T. Clusters of flowers d and e, with appropriate branches, embellish the field B. The lower field, C, contains within a principal rectangle, f, a prominent bouquet of flowers and leaves, g.

The difference between the style and character of the foliage in the three principal subdivisions, A, B, and C, imparts a characteristic appearance to this design.

I claim—

1. The design for a carpet, consisting of the diagonal zigzag figure A, having inclosed geometrical groundwork a, substantially as shown.

2. The design for a carpet, consisting of the field B, having figure b and floral clusters d and e, substantially as shown.

3. The design for a carpet, consisting of the field C, having figure f and bouquet g, substantially as shown.

4. The design for a carpet, consisting of the figures A, B, and C, which are ornamented by the figures b, d, e, f, and g, substantially as shown.

HENRY HORAN.
